REPEATING ALARM TIMER

Henry E. Warren, Ashland, Mass., assignor to
 Warren Telechron Company, Ashland, Mass.,
 a corporation of Massachusetts

Application September 29, 1937, Serial No. 166,368

7 Claims. (Cl. 161—23)

My invention relates to timing devices of the type which is intended to produce an alarm or other signal at the end of a predetermined and preferably adjustable period of time subsequent to setting the timer into operation or to time other events, to count the number of revolutions of a motor, etc. Such a device is useful for example for timing processes and to notify an attendant when the time for completing a certain process has expired.

In carrying my invention into effect, I preferably employ a constant speed alternating current motor as the timing element of the device and utilize the alternating flux of the motor for sounding an alarm at the expiration of the time period for which the device is set. Such alarm signal is preferably repeated at every few seconds until shut off by deenergization of the timing motor.

The features of my invention which are believed to be novel and patentable will be pointed out in the claims appended hereto. For a better understanding of my invention, reference is made in the following description to the accompanying drawing in which Fig. 1 shows a perspective exploded view of the essential parts of a repeating alarm timer constructed in accordance with the present invention; and Fig. 2 represents a modified form of timer arranged to sound a continuous alarm at the end of the timing interval.

Referring to Fig. 1, 10 represents the stator of a self-starting synchronous timer motor, the rotor of which together with suitable reduction gearing is contained in the barrel 11 and from which a timer operating shaft 12, driven by the motor, extends. Shaft 12 carries a gear 13 which may mesh with a gear 14 secured on a shaft 15. Shaft 15 is rotatively mounted in a bearing 16 on a framework 17. Framework 17 is secured to the near end of a shaft 18 pivoted on its own axis in supporting structure not shown. Shaft 18 is of resilient material and has some torsional spring action and has secured to it, adjacent its far end, a magnetic bar 20, which comprises an armature with respect to pole pieces 21 and 22 projecting from the motor stator on opposite sides of the motor energizing winding 23. A spring 19 is provided which tends to rotate shaft 18 in a counterclockwise direction, retracting armature 20 away from its pole pieces and moving gear 14 to the right and out of mesh with gear 13. The axes of rotation of gears 13, 14 and frame 17 are parallel. Rotary motion of shaft 18 and the parts attached thereto is limited by a stop such as the stop pin 24.

When the motor is energized from a suitable source of alternating current, designated at 48, the major portion of its flux traverses the rotary armature air gap and shaft 12 is driven at a constant speed. A certain amount of leakage flux tends to cross through armature 20 between pole pieces 21 and 22 and the armature is attracted into contact with such pole pieces rotating shaft 18 clockwise and swinging shaft 15 slightly to the left of the position shown, and engaging gears 13 and 14 in driving relation.

When the motor is deenergized the armature 20 is retracted as shown and the frame 17 rests against stop 24 due to the action of spring 19, with gears 13 and 14 disengaged. As thus far described, then, the motor performs two functions, as follows: It serves to drive gear 13 at a constant speed when the motor is energized, and it serves to engage and disengage gears 13 and 14 to and from driving relation as the motor is energized and deenergized.

Gear 14 is on a shaft with a gear 25 which meshes at all times in driving relation with a gear 26. Gear 26 is secured to a time setting shaft 27 which carries a pointer indicator 28 on its front end and a collar 29 on its rear end. A spring 30 is provided for returning time setting shaft 27 counter-clockwise to an initial position when gears 13 and 14 are completely disengaged. Spring 30 is secured between collar 29 and some stationary structure so as to be wound up when shaft 27 is rotated in a clockwise direction by motor 10. It then serves to return the shaft 27 together with pointer 28, counterclockwise, to an initial position as soon as the motor is deenergized, to disengage the clutch comprising gears 13 and 14. The initial position of shaft 27 is determined by a stop finger 31 projecting from the side periphery of gear 26 and which is rotated by spring 30 into engagement with pinion 25 as a stop when gear 14 is disengaged from driving relation with gear 13. This initial position of time setting shaft 27 is then when stop finger 31 rests against pinion 25, and preferably when pointer 28 is pointing straight up.

Concentric with shaft 27 and cooperating with pointer 28 is a time setting dial 32. Dial 32 is normally stationary, it being held against rotation by friction. For this purpose the dial is secured to a hollow shaft 33, carrying collars 34 and 37 on opposite sides of a plate 35 comprising one of the stationary supporting plates of the device. A resilient friction clutch member 36 is pressed between plate 35 and collar 37 with suf-

5 ficient force to hold shaft 33 and dial 32 from rotation except when dial 32 is manually turned in an adjusting operation. For convenience in manually adjusting dial plate 32 it is made in the
5 form of a gear wheel and meshes with a small gear 38 which is provided with a knurled thumb piece 39 for rotating the same.

10 The dial plate 32 is provided with a stop for pointer 28. In this instance I have shown the stop as including a contact device, although the contact feature may be omitted. The actual stop comprises a pin 40 of insulating material protruding from the side of dial 32 in the path of rotation of pointer 28. However, in front of stop
15 pin 40 I have provided a pair of normally open resilient contact fingers 41 and 42 secured to the side of dial 32 at 43. These contact fingers are so arranged in the path of pointer 28 as it approaches stop pin 40 that their contact points will be pressed together as the finger 28 reaches
20 stopping position. This contact device is illustrated as for the purpose of closing the circuit 44 of a relay 45 which may be utilized for any desired purpose, such, for example, as the stopping
25 of a process operation being timed by the timer mechanism.

30 The stopping position of pointer 28 as determined by stop 40 is preferably opposite the zero graduation mark on dial 32 and the dial is graduated from this point in a counterclockwise direction with suitable time indications, such as seconds, minutes or hours, depending upon what time range is desired and the rate at which the pointer 28 is normally driven by the timing motor 10. For the purpose of the present illustration it may be assumed that the dial is graduated
35 in minutes and that if the dial is set so that pointer 28, when in its initial or up-right position, is opposite 15 on the dial, it will require 40 15 minutes for the pointer 28 to be driven to the zero mark and stopping point. It is important that when pointer 28 comes against stop 40 it will be positively stopped and will not rotate dial 32 through friction clutch 35, 36.

45 I make use of the stopping action of pointer 28 and the continued driving action of motor 10 at the end of a time cycle to cause the armature 20 to produce a penetrating audible signal which is repeated every few seconds until motor
50 10 is deenergized. This audible signaling action will occur at the end of a timing operation and will be explained when we come to that point in reviewing the manner of setting, operating and resetting the device for normal use.

55 Let it be assumed that the timer is to be used in connection with the development of photograph negatives, that it is desirable to leave the photograph negatives in the developing solution for 15 minutes. The circuit of motor 10 is opened
60 at a switch 46 which may, for sake of convenience, be located in the dark room. The timer mechanism may be located in the same or some other room. The attendant first sets dial 32 for 15 minute operation by turning the dial by means
65 of knob 39 until it reads 15 minutes with respect to pointer 28. It should be observed that with motor 10 deenergized gear 14 will be demeshed from gear 13 and spring 30 will have rotated finger 31 against stop gear 25 so that pointer 28
70 will point straight up. The attendant then places his negatives in the developing solution and closes switch 46 and goes about some other work. When the motor is energized, armature 20 is attracted to pole pieces 21 and 22, gear 14 is meshed with
75 gear 13 and the motor starts into operation.

Pointer 28 is driven towards the zero graduation on dial 32 at such a constant rate as to reach this point in 15 minutes, stop finger is rotated away from gear 25 and spring 30 is wound up. The direction of rotation of the gears 13 and 14 during this timing cycle are as indicated by arrows. At the end of 15 minutes pointer 28 is stopped by stop 40 which blocks gears 26, 25 and 14 from further rotation. The driving action of motor 10 continues and gear 13 is rotated in such direction with respect to blocked gear 14 that frame 17 is forced to the right, rotating resilient shaft 18 counterclockwise and forcing armature 20 away from pole pieces 21, 22. The motor is still energized so that armature 20 now starts to chatter under the influence of the flux pulsations tending to draw it to the pole pieces and the opposing force tending to pull it away. The resiliency of shaft 18 augments this chattering action. As the armature is pulled further and further away the chattering becomes louder and louder until gears 13 and 14 have moved far enough out of mesh to allow gear 13 to slip one tooth. This momentarily relieves the pulling away effect on armature 20 and it is drawn toward the pole pieces. This action and the resulting audible noise cycle is repeated over and over as the teeth of gear 13 slip by the teeth in gear 14. As a result of this action there occurs a series of short penetrating sound signals each having a rising inflection, each such signal lasting for a few seconds and being almost immediately repeated. This notifies the attendant and he proceeds to stop the development process and as soon as convenient, he deenergizes the motor 10. As soon as motor 10 is deenergized, magnetic pull on armature 20 is relieved and gear 14 swings to full demeshed position with respect to gear 13. The driving connection between the motor and indicator 28 is interrupted. Spring 30 now returns stop finger 31 against gear 25 and pointer 28 to initial position and the device is ready for another timing operation.

45 The use of gear 25 as a stop for finger 31 is not considered to be essential but it is helpful in preventing any rebound action of frame 17 which might tend to reengage gear 14 with gear 13. It will be noted that this stopping action of finger 31 against gear 25 is in a direction to tend to disengage gears 13 and 14. It will be noted that I have shown a shading coil 47 about a portion of pole piece 22. This is desirable to reduce magnetic hum of armature 20 when motor 10 is energized and when the armature is not intended to chatter. During audible signal operating motor 10 continues to run at constant speed. The frequency at which the audible signal will be repeated will depend upon the number of teeth in gear 13 and its rate of rotation. Generally, it will be desirable to have this signal repeat itself every few seconds and to arrange the speed of shaft 12 and the number of teeth in gear 13 accordingly. If shaft 12 runs at 1 R. P. M. and gear 13 has 20 teeth, the audible signal cycle will have a duration of three seconds. The gear ratio of the train beyond this point to shaft 27 will depend upon the time range desired on dial 32. It will be evident that the motor actuated audible signaling arrangement described may be employed in any motor driven gear train where it becomes desirable for any reason to give such a signal when the drive to a load through the gear train becomes blocked.

70 It will be seen that the arrangement is such that the entire operation of the timer is con- 75

trolled by one simple switch such as the switch 46 in the circuit of the timer motor, and that this switch may be placed anywhere in the motor energizing circuit either adjacent to or some distance from the timer. Or, if more convenient, several such switches may be provided in series in the motor circuit so that the timer operation may be started by closing one switch 46 and stopping the operation by opening another switch 10 46' located in another room. All timer operations are performed in their proper sequence by the single time motor as thus controlled and include starting a timing operation by closing the motor circuit, sounding a signal at the end of such 15 operation, and, if desired, performing some additional controlling operation through the relay circuit 44 controlled by contacts 41—42, and stopping the audible signal, opening control contacts 41—42, and resetting the entire device for a subsequent timing operation upon opening the motor circuit.

It should also be observed that the timing operation may be stopped and the device reset at any time before pointer 28 reaches stop 40, should that be desired, by simply opening the circuit of motor 10, in which case armature 20 would not produce the audible signal. The normal timer operating period may be increased or decreased within the time range of dial 32 by rotary adjustment of such dial and such adjustment may be made before setting the device into operation or during its operation. The device may be used to perform a timing operation and automatically repeat such operation by including the normally closed contacts of a time delay relay shown at 45a in the circuit of motor 10 and connecting the coil of this relay in the circuit of contacts 41—42. When the indicator 28 reaches stopping position, the contacts are closed and relay 45a energized 40 and the motor 10 deenergized. The electromagnetic clutch interrupts the driving connection at gears 13—14, indicator 28 returns to its initial position, contacts 41—42 open and the motor is again energized and repeats its operation. The 45 time delay of relay 45a may be such as to allow the alarm to sound as well as to allow the timer to reset. The device may be made to start or stop or both start and stop in response to any event to be timed. For example, let us suppose 50 that the switch 46' represents a thermostat switch responsive to temperature in a steam sterilizer, in which case the timer would respond to the closing and opening of the thermostat switch and would give the time during which the temperature was uninterruptedly maintained above that corresponding to the setting of the thermostat and would sound an alarm if such temperature was maintained longer than necessary and the timer would reset without sounding an alarm if the temperature was not maintained long enough. Other uninterrupted processes or events may be timed in an analogous manner.

Likewise, the device will be useful in many cases where the motor 10, instead of measuring time, measures speed or some other quantity, and the alarm is sounded after a certain number of revolutions independent of time. Hence, I do not wish to limit my invention to using a constant speed motor at 10.

70 In Fig. 2 I have represented a modified form of timer employing several of the features of the timer of Fig. 1. Those parts which are similar in the two figures are indicated by like reference characters.

75 In Fig. 2 the clutch operating arrangement for

shifting gear 14 out of mesh with gear 13 has been modified slightly because in this modification I do not depend upon the chattering action of armature 50 to produce a noise directly by striking its pole pieces. Instead, I mount a resilient bell clapper 51 on armature 50 and cause the hammer of this clapper to strike a bell 52 when armature 50 is set into vibration at the end of a time cycle. The outer end of armature 50 is connected to frame 53 by rod 54. Frame 53 is pivoted at 55 and is biased towards stop 24 by spring 56. The lower swinging end of frame 53 rotatively supports shaft 15. In this figure as in Fig. 1 the parts have been shown considerably spread apart and it will be understood that in actual construction, shaft 15 will be short and gears 14 and 25 will be close together and close to the bearing of shaft 15 in framework 53 so as to make a practicable construction.

In Fig. 2 gear 26 is not fixed on shaft 27 but is connected thereto through a friction clutch, a part of which is shown at 57. The dial plate 58 is fixed and has a fixed stop pin 59 for pointer 28. The initial position of pointer 28 is determined by a stop hand 60. Hand 60 is rotatively adjustable with respect to plate 58 but remains in any position of adjustment by reason of a friction coupling 61 between it and plate 58. Hand 60 has a projection 62 which catches and stops hand 28 when the latter returns to its initial position against stop 62 when reset at the end of a timing operation. The distance of stop hand 60 from the stop pin 59 determines the time setting of the device.

The operation of this device is as follows. Stop hand 60 is set away from stop pin 59, a distance corresponding to the time setting desired. Spring 30 will rotate pointer 58 counter-clockwise against stop 62, when gears 13 and 14 are disengaged in any position of the stop hand 60. Motor 10 is then energized, armature 50 is attracted, and the bell receives one stroke of hammer 51. Gear 14 is engaged in driving relation with gear 13. The motor starts into operation simultaneously and pointer 28 is driven from an initial position opposite hand 60, clockwise towards stop pin 59. Clutch 57 does not slip during this part of the cycle, and hence shaft 27 winds up spring 30. When pointer 28 is stopped at post 59 at the end of the time cycle, clutch 57 starts to slip and the torque transmitted through gears 13 and 14 is accordingly materially increased, which tends to swing frame 53 counterclockwise and move armature 50 away from its pole pieces against the pulsating magnetic attraction of the motor field. As a result, the bell clapper is vibrated and rings bell 52.

It is unnecessary that the gears 14 will move away from gear 13 far enough to cause gear 13 to slip its teeth in order to cause a vigorous ringing of the bell. Of course, the friction at 57 may be made sufficient to block gear 14, in which case gear 13 will move gear 14 to the right until the tooth in 13 slips by the adjacent teeth of gear 14 so as to periodically vary the outer limit of vibration of armature 50. This will cause some pulsating change in the sound of the alarm, as in Fig. 1. If such operation is desired, the friction clutch at 57 would not be essential.

When the motor 10 is deenergized, gear 14 is 70 demeshed from gear 13 and the spring 30 returns pointer 28 to starting position against stop 62 of hand 60, wherever it may be set. This gear demeshing and pointer resetting action is desirable whether an alarm be included or not and

such resetting operation may, of course, occur before pointer 58 reaches post 59, should that become desirable. The hand 60 and pointer 28 are preferably painted different colors in order that an operator, who may wish to observe the device during its operation to see how much time is left during a timing operation, may more easily distinguish the pointer 28. Control contacts may be included on dial plate 58, as in Fig. 1, if that is desired.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States is:

1. An alarm timer, including a movable indicator, an alternating current electric motor, a driving connection including a pair of rotatively mounted intermeshed gears between said motor and indicator whereby the latter may be driven forward to indicate the number of rotations of said motor, a support for one of said gears pivoted on an axis of rotation parallel to the axes of rotation of said gears, resilient means tending to rotate said support to swing the gear carried thereby out of mesh with the other gear to interrupt said driving connection, a magnetic armature connected to said support and positioned to be attracted to the electric motor when the latter is energized to move said support against the action of said resilient means to establish said driving connection, the direction of rotation of the gears by said motor when the indicator is driven by the motor thereby also tending to rotate said support to swing the gear carried thereby out of mesh with the other gear, this last mentioned tendency plus the tendency of said resilient means being insufficient to overcome the attraction of said armature to interrupt said driving connection when the motor is energized and the indicator is being normally driven, means between said gears and indicator for blocking further forward movement of the indicator after it has been driven forward by a predetermined amount, said blocking action and the continued operation of said motor causing the torque between said gears to increase by an amount sufficient to cause movement of the armature away from its attracted position and permit it to vibrate, said armature comprising a portion of an audible alarm which is operated by such vibration until the motor is deenergized.

2. In combination, a device to be driven in a given direction, an alternating current motor, a driving connection between said device and motor, said connection including a pair of gears, one of which is bodily movable from a position in driving relation with the other gear away therefrom to a position where said driving connection is interrupted, the bodily movement of said gear from driving position to the interrupted position being in the same direction in which said bodily movable gear tends to move by the transmission of power through said gears from the motor to the driven device when the latter is driven in said given direction, a pivoted support on which the bodily movable gear is rotatively mounted, a magnetic armature connected to said support and positioned to be attracted to said motor when the latter is energized

to rotate said support and move its bodily movable gear to driving position, resilient means tending to rotate said support and move its bodily movable gear to the interrupted position, said parts being so adjusted that when the motor is energized and the torque transmitted through said gears is normal, the driving connection is maintained, and when the torque transmitted through said gears is in excess of normal, the armature is pulled away from the motor and is caused to vibrate and sound an alarm.

3. In combination, an alarm mechanism, a device to be driven in a given direction, an alternating current motor, a driving connection between said motor and device, including a pair of toothed gears pivoted for rotation on parallel axes, a frame pivoted to swing about an axis parallel to the axis of rotation of said gears and supporting one of said gears so as to move the same into and out of mesh with the other gear the direction of rotation of said gears being such as to tend to move the frame supported gear out of mesh with the other gear when the motor is in operation and driving said device in said given direction, resilient means also tending to swing said frame in the direction to demesh said gears, said alarm mechanism including a pivoted magnetic armature which is attracted to the motor when the latter is energized, a torsionally resilient shaft on which said armature and frame are both secured in spaced relation, the adjustment being such that when the motor is energised and the armature is attracted thereto, the gears are meshed in driving relation against the tendency of said resilient means and the normal driving action of said gears to move them apart and when the driving connection on the driven side of said gears is blocked, the motor continues to operate and moves said gears apart until their teeth slip with respect to each other, such slipping action of the gears being accompanied by a variable movement of the armature away from attracted position and intense vibration thereof productive of an audible sound which varies in intensity in cyclic relation to the slipping action of the gear teeth.

4. An alarm timer, comprising a time graduated dial, an indicator movable with respect to said dial, a synchronous motor, a driving connection between said motor and indicator whereby the indicator may be driven with respect to said dial to indicate the passage of time, said driving connection including disconnecting clutch means, electromagnetic means energized when the motor is energized for operating said clutch means to complete said driving connection, resilient means effective when the motor is deenergized to operate said clutch means to interrupt said driving connection, a stop on the indicator side of the clutch means for stopping time indicating movement of said indicator after it has been driven for a predetermined adjustable time, such stopping action and the continued operation of said motor causing clipping action of the clutch means, an alarm operated by the electromagnet means in response to such slipping action and the continued operation of said motor and a spring which is wound when the indicator is driven for returning the indicator to an initial position when the motor is deenergized.

5. An alarm timer comprising a time graduated dial, an indicator movable with respect to said dial and having an initial position with respect to said dial which is adjustable, a synchronous motor for driving said indicator over said dial

from such initial position to indicate the passage of time, stop means for stopping the movement of said indicator after it has been driven by said motor for a time corresponding to the position of initial adjustment with respect to said dial, a driving connection between the motor and indicator which includes disconnecting clutch means, electromagnetic means energized and deenergized when the motor is energized and deenergized for operating said clutch means to respectively complete and interrupt said driving connection, a spring between the clutch means and the indicator which is wound when the indicator is driven by the motor for returning the indicator to its initial position when the motor is deenergized, and an alarm operated by vibration of said electromagnetic means when said indicator is driven against its stop and the motor remains energized.

6. A timer comprising a movable time indicator, a synchronous motor, a driving connection between said motor and indicator whereby the latter may be driven by said motor at a constant speed to indicate the passage of time, said driving connection including a gear driven by the motor, a gear for driving the indicator, a shaft, and a pair of intermediate gears mounted on said shaft, one meshing with the motor driven gear and the other meshing with the indicator driving gear, a pivoted frame on which said intermediate gears and their shaft are mounted which frame may swing between a position where said gears are in mesh to complete the driving connection to a position where the gear-train is interrupted at the motor driven gear, a spring connected with said indicator which is wound up when the indicator is driven by said motor for returning said

indicator to an initial position when the driving connection is interrupted, a projection on the indicator driving gear which is rotated into contact with its intermeshing gear on said frame as a stop for determining the initial position of said indicator, said stopping action being in a direction to urge the pivoted frame towards its gear-train interrupting position, and means responsive to the energization and deenergization of said motor for moving said frame to respectively complete and interrupt said driving connection.

7. An alarm timer comprising an indicator, a synchronous motor having an exposed magnetic field structure, a drive-connection between said motor and indicator for driving the latter at a constant rate to indicate the passage of time, said driving connection including a gear-train, a frame on which a portion of said gear-train is carried, said frame being pivoted for limited movement, a magnetic armature connected to said frame and being positioned to be attracted to the field structure of said motor when the latter is energized, a stop for stopping the time indicating movement of said indicator after it has been driven by the motor for a predetermined time interval, said stopping action and the continued operation of said motor serving to cause relative movement of said frame and a retraction of the magnetic armature from its attracted position against the field structure to a position where the armature is caused to vibrate under the influence of the alternating flux of said field and set up an audible sound which continues until the motor is deenergized.

HENRY E. WARREN.
